CAR ROOF

Application filed January 20, 1932. Serial No. 587,613.

This invention relates to car roofs of the type wherein the roof sheets are provided with flanges along their side margins that extend downwardly into channels or spaces in carline members. The principal objects of the invention are to make the joints watertight, to make the sheets cooperate with the carline members in taking care of the stresses due to vertical load, wearing of the car frame and the like, to devise a new and improved composite carline, and obtain other advantages hereinafter appearing.

The invention consists principally in clamping together the members of a composite carline with downturned flanges of the roof sheets interposed between said members. It also consists in the parts, combinations and arrangements of parts hereinafter described and claimed.

20. In the accompanying drawings, wherein like reference numerals refer to like parts wherever they occur,

Fig. 1 is a plain view of the portion of car roof embodying my invention,

25. Fig. 2 is a vertical transverse section through one-half of the roof on the line 2—2 in Fig. 1;

Fig. 3 is a vertical transverse section through the car at the eaves on the line 3—3 30 in Fig. 1;

Fig. 4 is a fragmentary side elevation of a roof at one of the carlines;

Fig. 5 is a vertical cross-section on the line 5—5 in Fig. 3;

35. Fig. 6 is a vertical cross-section on the line 6—6 in Fig. 2;

Fig. 7 is a vertical transverse section similar to Fig. 3 showing a modified carline construction;

40. Fig. 8 is a fragmentary side elevation of a roof in the region of the end of the carline;

Fig. 9 is a vertical cross-section on the line 9—9 in Fig. 7; and

45. Fig. 10 is a similar cross-section on the line 10—10 in Fig. 7.

According to the present invention, each main carline member 1 of substantially channel-shaped cross-section which extends from side plate 2 to side plate 2 and preferably has outstanding flanges 3 at its upper edges that are turned down at the ends of the carline to form end flanges 4 that bear against the inner faces of the side plates. Preferably the top of each main carline member 1 extends higher than the side plates 2 and the end flanges 4 of said carline member are riveted to said side plates by horizontal rivets 5.

The roof sheets 6 extend entirely across the car and have downturned flanges 7 at their ends that overlap the side plates and preferably are riveted thereto by horizontal rivets 8. Said sheets also have downturned flanges 9 along their side margins which flanges extend into the channels of the main carline members 1, adjacent flanges being somewhat spaced apart. Secondary carline members 10 are interposed between the downturned flanges 9 of the roof sheets 6 and are of suitable cross-sectional shape for effectively wedging or locking the sheet flanges and the carline members together.

In the construction illustrated in Figs. 5 and 6, the secondary carline member 10 has concave sides that are well adapted for cooperation with the convex inner walls of the main channel member 1. In this design of secondary carline member, there is a considerable concentration of metal in the upper portion thereof which is substantially flush with the roof sheets. In the construction illustrated in Figs. 9 and 10, the main carline member 1a has flat sides and the secondary carline member 10a is an elongated sheet or plate folded lengthwise on itself with the two plies spaced slightly apart and with the opening down. In both cases, the ends of the secondary member are spread out or widened and turned down, as at 11 and 11a, respectively, beyond the side plates to which sides they are secured by horizontal bolts or rivets, pref.

erably the same fasteners 5 that secure the main carline members.

After the roof sheets have been placed with their side flanges in the channels of the main carline members and the secondary carline members have been placed between said sheet flanges, said carline members and sheet flanges are clamped together tightly preferably by means of bolts or rivets 12 which extend horizontally through the side walls of the channel member, the flanges of the sheets and the secondary carline members.

In assembling the roof it is desirable to have the holes for the bolts or rivets 12 so located in the sheet flanges and secondary carline members that, when the sheets are loosely laid on the carlines, such holes will be slightly higher than the holes in the walls of the channel member; so that, when the rivets or bolts 12 are tightened, they will pull the roof sheets down firmly onto the tops of said channel members. Prior to such riveting or clamping, the void spaces in the channels of the main carline members 1 are filled with suitable plastic cement 13, such, for instance, as that known as reforite. As such cement is plastic, it permits the metallic parts to be tightly clamped together and itself is squeezed or extended into all void spaces in the channels and also fills the angles between the roof sheets and the secondary carline members, thereby not only making a watertight joint but protecting adjacent portions of the sheets from the rusting, corrosion and abrasion to which such portions of the sheets would otherwise be subject by reason of the accumulation thereon of moisture and cinders.

By reason of the carline members and sheet flanges being solidly or rigidly clamped together, they function as a unitary structure in taking care of the stresses to which carlines are subject in service; that is, instead of the channel-shaped member alone constituting a carline with the roof sheets constituting a load thereon, the marginal portions of the roof sheets and the secondary members of the carline cooperate directly with the channel-shaped member in taking care of all stresses. Consequently, both the carline members and the roof sheets, or either of them, may be lighter for equal strength than where the carline consists of channel-shaped members alone.

What I claim is:

1. A car roof comprising channel-shaped carline members extending from side plate to side plate, roof sheets on said members with side marginal flanges extending into the channels thereof, and secondary carline members between said sheet flanges, all clamped together horizontally.

2. A car roof comprising channel-shaped carline members extending from side plate to side plate, roof sheets on said members

with side marginal flanges extending into the channels thereof, and secondary carline members between said sheet flanges, all clamped together horizontally, said secondary carline members having widened ends secured to the outer sides of the side plates.

3. A car roof comprising channel-shaped carline members extending from side plate to side plate, roof sheets on said members with side marginal flanges, extending into the channels thereof, and secondary carline members between said sheet flanges, all clamped together horizontally, the space in said channel member not otherwise occupied being filled with cement.

4. A car roof comprising channel carline members secured to the inner sides of the side plates with their tops extending higher than said side plates, roof sheets with side flanges extending into the channels, and secondary carline members between said flanges with their tops substantially flush with said sheets, said carline members and flanges being clamped together horizontally.

5. A car roof comprising channel carline members secured to the inner sides of the side plates with their tops extending higher than said side plates, roof sheets with side flanges extending into the channels, secondary carline members between said flanges with their tops substantially flush with said sheets, said carline members and flanges being clamped together horizontally, and said secondary members having widened ends secured to the outer sides of said side plates.

6. A car roof comprising channel carline members secured to the inner sides of the side plates with their tops extending higher than said side plates, roof sheets with side flanges extending into the channels, secondary carline members between said flanges with their tops substantially flush with said sheets, said carline members and flanges being clamped together horizontally, and said secondary members having widened ends secured to the outer sides of said side plates, the space in the channels not otherwise occupied being filled with cement.

7. A car roof comprising main carline members secured against the inner sides of the side plates, said members being of channel shape with their side walls convex inwardly and with lateral top flanges, roof sheets with side flanges extending into said channels, and secondary carline members with concave sides, said secondary members being disposed between the sheet flanges and having widened ends secured against the outer sides of the side plates, said carline members and sheet flanges being clamped together horizontally.

8. A car roof comprising main carline members secured against the inner sides of the side plates, said members being of channel shape with their side walls convex inwardly

and with lateral top flanges, roof sheets with side flanges extending into said channels, secondary carline members with concave sides, said secondary members being disposed between the sheet flanges and having widened ends secured against the outer sides of the side plates, said carline members and sheet flanges being clamped together horizontally, and the space in the channels not otherwise occupied being filled with cement.

Signed at Montreal, Canada, this 11th day of January, 1932.

RALPH BAND WINSHIP.
